(57) **CLAIM**

We claim the ornamental design for a transformer, as shown and described.

DESCRIPTION

FIG. 1 is a perspective view of the transformer showing the new design, with the front panel of the transformer open; FIG. 2 is a front elevational view of the transformer depicted in FIG. 1;

FIG. 3 is a rear elevational view of the transformer depicted in FIG. 1;

FIG. 4 is a right side elevational view of the transformer depicted in FIG. 1,

FIG. 5 is a left side elevational view of the transformer depicted in FIG. 1;

FIG. 6 is a top plan view of the transformer depicted in FIG. 1; and

FIG. 7 is a bottom plan view of the transformer depicted in FIG. 1.

FIG. 8 is a perspective view of the transformer showing the new design, with the front panel of the transformer closed; FIG. 9 is a front elevational view of the transformer depicted in FIG. 8;

FIG. 10 is a rear elevational view of the transformer depicted in FIG. 8;

FIG. 11 is a right side elevational view of the transformer depicted in FIG. 8;

FIG. 12 is a left side elevational view of the transformer depicted in FIG. 8;

FIG. 13 is a top plan view of the transformer depicted in FIG. 8; and,

FIG. 14 is a bottom plan view of the transformer depicted in FIG. 8.

The broken lines shown represent unclaimed subject matter and form no part of the claimed design.
